(57) **CLAIM**

The ornamental design for a bezel faceplate for an electrical receptacle as shown and described.

DESCRIPTION

FIG. 1 is a perspective view of a bezel faceplate for an electrical receptacle showing my new design;

FIG. 2 is a front view thereof;

FIG. 3 is a rear view thereof;

FIG. 4 is a side view thereof, the opposite side being substantially identical thereto;

FIG. 5 is an end view thereof, the opposite end being substantially identical thereto;

FIG. 6 is a perspective view of another embodiment of the bezel faceplate for an electrical receptacle showing my new design; and,

FIG. 7 is a front view of the embodiment shown in FIG. 6.

1 Claim, 6 Drawing Sheets
